UNITED STATES PATENT OFFICE.

WILFRED BANCROFT, OF ARDMORE, PENNSYLVANIA, ASSIGNOR TO LANSTON MONO-
TYPE MACHINE COMPANY, OF PHILADELPHIA, PENNSYLVANIA, A CORPORATION
OF VIRGINIA.

DEVICE FOR MEASURING TYPEWRITTEN MATTER.

1,355,881.

Specification of Letters Patent.

Patented Oct. 19, 1920.

Application filed November 2, 1916. Serial No. 129,133.

To all whom it may concern:

Be it known that I, WILFRED BANCROFT, a citizen of the United States, residing at Ardmore, in the county of Montgomery and 5 State of Pennsylvania, have invented a certain new and useful Device for Measuring Typewritten Matter; and I do hereby declare the following to be a full, clear, and exact description of the same, reference being had to the accompanying drawing, forming a part of this specification, and to the characters of reference thereon.

My invention relates to the measurement of typewritten matter and has particular 15 value in connection with the art of printing wherein it is now the almost universal practice to produce printed matter from copy which is typewritten. The amount of printed matter that a given number of pages 20 of typewriting will produce may be accurately estimated in advance by measuring or counting for each page the number of characters and spaces thereon, multiplying this number by a constant to convert the number 25 of characters and spaces into a printing unit of measurement and adding together these units obtained for each separate page. The utility of this system is practically confined to the users of the well known type- 30 setting machines which are now and have been for a number of years made and sold by Lanston Monotype Machine Company the product of such machines being based upon a system of type measurement in 35 which there is always a definite relation between the linewise widths of the various types constituting a font, which relation is the same for the same kind of faces, as for example, for all Roman faces, irrespective 40 of their point size or their design. On account of this uniformity of relationship between the width of set measurements of all such type, one constant in the above estimating system is sufficient for all type of the 45 same kind, importantly for all Roman type, of which type class practically all of modern printing belongs. This constant, which is the fraction 25/53 for Roman type, has been established by the making of a multi- 50 tude of comparisons between typewritten copy and the printed matter produced therefrom, and means that 53 typewritten characters and spaces (all of which, of course,

are of the same width) will produce 25 set ems of printed matter in Roman type, a set 55 em being the actual width in points of the widest letter of a font. A set em is, therefore, the em of the set size of a face and is so named to avoid confusion with the historic printers' em which is the em of the 60 point size of a face. The machines above referred to are designed and built upon the set em basis of measurement of the product so that the constant 25/53, or the slightly 65 different ratio for italic, boldface type, etc., does not necessitate the employment of a measurement or a term unfamiliar with those acquainted with the printing art. When the number of set ems which a given 70 copy will produce has thus been ascertained, the number of pages or columns of printed matter of a desired kind and size of type can readily be determined, or if the number of pages or columns is fixed the size of type, 75 with or without leading, for filling that fixed number of pages or columns can be readily arrived at. In other words, the determination of set ems makes it possible for a printer to predict with an accuracy that varies only a few per cent. just how large 80 a job he has before him, and he is thus enabled to estimate the cost thereof with the same accuracy.

One of the essential elements in the employment of the system, which is well 85 known under the expression "copyfitting," is the ascertainment of the number of characters and spaces of typewritten matter for each page. The device of my invention is particularly designed to facilitate and make 90 certain the desired results. In the drawings the device is illustrated in plan and as applied to a page 2 of typewriting. It consists of a sheet 1 generally triangular in form and having two edges, the top edge 3 95 and the side edge 4 meeting at right angles, the sheet being preferably thin and sufficiently transparent, as when made of celluloid or the like, that the typewriting lines may be distinguished by looking through the sheet when it is in place. This transparency may extend, as shown, throughout the entire sheet or it may be confined to the region of the side edge 4.

Along the top edge 3, or near it, graduations 5 are made, the spaces thus indicated

being each a unit of measurement equal to and representing the width of a typewritten character. Conveniently certain of the graduations are marked with numbers 5 showing how many graduations the marked ones are removed from the zero point, which point marks the beginning of the first unit of measurement of the letter scale and is at the extreme right of the top edge, *i. e.*, 10 where the top and side edges intersect. The first of these marks as shown, on the top or letter scale, beginning at zero and reading toward the left, is 10, no counting less than 15 ten being necessary because no typewritten line is ordinarily less than ten characters and spaces long.

In proximity to the side edge 4 another scale 6 is provided which may be called the line scale, its graduations representing as a 20 unit of measurement the distance between successive single spaced lines of typewriting. The top edge 3 takes the place and represents the first of these graduations, and thus marks the beginning of the second unit of 25 measurement of the line scale, the zero of the scale being one graduation above this edge and, therefore, outside of the boundaries of the device. Preferably every fifth graduation of this scale 6 is emphasized and 30 marked with a number indicating its position from zero.

In the use of the device it is placed upon a typewritten page so that the top edge 3 just touches the bottom of the first line of 35 copy. The device is now moved to the right or left, without displacing its top edge with respect to the first line of copy until the user by looking through the transparent gage positions the side edge, which is perpendicular to the typewritten lines, with approximately as many letters of the long lines at the right of said edge, as there are spaces at the ends of the short lines at the left of this edge of the device. Thus the 40 line lengths are averaged and when the device is thus positioned the number of letters or characters and spaces in the average line can be read on the letter scale and the number of lines can be read on the line scale.

50 The first line of copy is shown printed in the drawing and it will be noted that each letter and word-space occupies a space equal to the distance between the successive graduation lines 5. The remaining lines of the 55 copy are indicated by dotted lines. All of these lines begin at the 70 mark of the scale except those which begin paragraphs, which are indented four spaces. The various lines of copy end as shown, some short of the zero of the letter scale, which zero corresponds with the side edge 4, and some beyond said zero to the right of said edge 4. The ends of some of these lines are indicated by the reference character 7. It will be noted, 65 however, that the side edge 4 averages the

line lengths, so that the scale in the drawing shows that the average length of line is seventy characters and spaces. The device also shows without further positioning that the number of lines on the page is fifty-five. 70 The product of these two results is 3850, the number of characters and spaces on the page and this product multiplied by the ratio 25/53 gives 1816 which are the set ems of Roman type matter contained in the 75 page of copy measured. The number of set ems thus obtained may be used as a basis for a variety of determinations. For example, the printer is able readily to determine the size of type and leading required 80 to fill with these set ems of matter a specified number of pages of a certain size; or to determine the number of printed pages these set ems will make when set in a specified face, measure and page size. Of course, 85 when a page of straight matter is interrupted by cuts and the like, especially when the cuts are of irregular shape, the area of the cuts to be placed on a given page must be subtracted from the area of the page in 90 order that the area of the printed matter the page will accommodate may be arrived at. This is conveniently done by the use of a chart representing the page and having spaces indicated thereon for each em of 95 printed matter to be placed on the page, the columnwise dimensions of said spaces being equal to the point size of the type font to be used and the linewise dimensions thereof being equal to the set size in points of the 100 widest type in the font to be used. A proof of the cut is usually secured to the chart in the location desired and an irregular line then drawn around it to mark the border between the cut and the printed matter. 105 The number of set ems occupied by the cut and likewise the number remaining on the page for receiving printed matter can of course be easily determined from the chart. Thus the areas of the page to be occupied 110 by cuts may be allowed for and the number of printed pages corresponding with a certain typewritten copy, including the cuts that may go with it, may be estimated accurately by the use of the typewriter gage with 115 the assistance of the chart.

There are in common use only two sizes of typewriter characters, the pica size in which there are ten letters to the inch and the elite size in which there are twelve letters to the inch, so that two devices would be sufficient for practical purpose, although it is obvious that both the pica and the elite scale could conveniently be placed upon a single device.

125 I claim:—

A device for measuring typewritten matter comprising a substantially triangular sheet of transparent material having a top edge bearing letter scale graduations and a 130

right side edge at right angles to said top edge and bearing line scale graduations, the unit of measurement of said letter scale being the width of a typewritten character and 5 the beginning of the first unit thereof coinciding with the line scale bearing edge, the unit of measurement of said line scale being

the distance between adjacent typewritten lines and the beginning of the second unit thereof coinciding with said letter scale 10 bearing edge, substantially as and for the purpose set forth.

WILFRED BANCROFT.
